UNITED STATES PATENT OFFICE.

CHARLES WALES, OF DETROIT, MICHIGAN, ASSIGNOR TO BURROUGHS ADDING MACHINE COMPANY, OF DETROIT, MICHIGAN, A CORPORATION OF MICHIGAN.

ADDING MACHINE.

1,132,753.

Specification of Letters Patent. Patented Mar. 23, 1915.

Application filed April 18, 1908. Serial No. 427,842.

To all whom it may concern:

Be it known that I, CHARLES WALES, a citizen of the United States, residing at Detroit, in the county of Wayne and State of Michigan, have invented certain new and useful Improvements in Adding-Machines, of which the following is a specification.

The present invention relates more particularly to that department of an adding and listing machine which comprises the depressible keys bearing various inscriptions denoting amounts and the depression of which ordinarily results in unlatching the adding mechanism and setting stops to determine the extent of movement thereof.

One object of the invention is to provide a form of means better adapted for use in an adding and listing machine organized to provide for an early release of depressed keys and the depression of some other or the same keys again before the cycle of operation of the machine is concluded. It will be obvious that in a machine so organized it will sometimes happen that one or more key stops may stand in the path of the abutment pieces of the adding mechanism as the same are returned to normal. The present invention provides a construction better adapted for the necessary coöperative action of such abutment pieces and key stops where the former must pass by the key stops in returning to normal and upon again advancing to perform the usual function of limiting the extent of movement of the adding mechanism by abutment against key stops or initial zero stops.

Another object of the invention is to adapt the keyboard and keyboard mechanism, including the key stops, to an adding machine organization in which the adding mechanism is in rear of the keyboard and the key stops therefore projected toward the rear of the machine by depression of keys. Novel means are provided whereby not only does the depression of an amount key result in projecting the connected key stop rearwardly into the path of the associated abutment piece, but also operates other connections of a simple and reliable character to withdraw from effective position the initial stop which, when no key is depressed in the row or bank and the machine is operated, serves to locate the zero type in printing position.

With these and incidental objects in view,

the invention consists of various novel features of construction and combinations of parts the essential elements of which are set forth in the appended claims and a preferred form of embodiment of which is illustrated in the accompanying drawings and described in detail hereinafter.

Of said drawings, Figure 1 represents in left side elevation a certain portion of an organized adding machine to which the improvements of the present invention are applied, all parts illustrated being shown at normal; Fig. 2 represents the key board in plan view partly broken away to disclose some parts on a lower plane, certain of which appear in horizontal section; Fig. 3 is a fragmentary sectional elevation illustrating the operation of a single amount key, (some parts being broken to economize space) the dotted lines illustrating the effect of depressing such key; Fig. 4 is a fragmentary rear elevation of the keyboard illustrating the means for temporarily holding keys depressed; and Fig. 5 represents a detached amount key in perspective.

The right hand one of a set of reciprocating segmental adding racks 6 is shown in Fig. 1, and one of a set of adding wheels 6^a in mesh therewith, the racks being mounted on sector-shaped carriers or levers 6^b. On curved downward extensions 60 of said carriers there are pivotally mounted abutment pieces 60^a with beveled fronts and straight top edges. Springs 60^b project the beveled portions of the abutment pieces forwardly beyond the front edges of said carrier extensions 60, holding said abutment pieces against projections struck up out of the carriers as shown in Fig. 1. There is erected within the casing of the machine, just forward of the segmental racks, a vertical plate 21 curved to correspond with the curvature of the segmental racks and apertured in vertical rows equi-distantly for the accommodation of stop blades in series of tens with any one of which the associated abutment piece 60^a may coöperate to determine the extent of movement of the rack carrying lever. Nine of these blades in each vertical row, the same being designated by the numeral 21^a, are normally retracted, these constituting the amount key stops and being formed upon the rear ends of rods 21^b having downwardly extending front portions obliquely slotted as at 21^c to receive

pins or studs 21^a on the lower ends of the stems 21^a of the amount keys 21^c respectively. The latter are arranged as usual in several parallel rows running from front to rear and the keys of each row inscribed with numerals from 1 to 9. The remaining stop blades 21^c normally protrude rearwardly from the plate 21 for the purpose of having the abutment pieces 60^a encounter them and thus limit the movement of the type carrying levers so as to set up the zero type for printing, it being understood that the rack carriers 6 will be suitably connected with type carrying levers.

15 The stems 21^a of the amount keys slide through slots in a keyboard plate 21^a and the key stems are further guided by slots in a series of transversely extending angle brackets 21ⁱ below the horizontal portions 20 of which extend the stop rods 21^b. The keys are normally upheld by springs 21^d surrounding the stems between suitable shoulders on the keys and the said brackets. It will be obvious that depression of any 25 key will cause rearward longitudinal movement of its stop rod by reason of the cam action between the stud 21^a and the oblique slot 21^c. The rods are supported and guided at their forward ends by cross rods 21^k which extend beneath them and run from side to side of the machine. The stop rods have short forward extensions 21^m so that one cross rod 21^k serves to support two stop rods of a series. For instance, the uppermost strip or rod of a series is supported at its forward end by reason of the engagement of its forward extension 21^m over the rod 21^k which extends under and supports the next lower stop rod or strip by engaging 35 under that portion thereof just in rear of the obliquely slotted portion. Thus the number of supporting cross rods can be reduced. The strips or rods are held from lateral displacement at their forward ends 40 by engagement with slots or notches in the vertical portions of the angle brackets 21ⁱ as indicated in Figs. 1 and 2, each rod being thus guided by two of the angle brackets by reason of the fact that the forward extension 21^m engages the notch of the next lower bracket to that one in which the rod engages just forward of its obliquely slotted portion.

45 It is not only necessary that the depression of an amount key shall thrust its associated stop blade into the path of the abutment piece 60^a, but by the same act the initial stop blade 21^c must of course be withdrawn from the path of said abutment piece. The initial stop blades are formed upon the 50 rear ends of rods 21^a which at their forward ends engage in notches of the lowermost angle bracket 21ⁱ and rest upon the lowermost cross rod 21^k as shown in Figs. 1 and 2. These initial stop rods have joined to 55 them near their forward ends thrust rods

21^a extending on an angle to the rods 21^a as shown in Fig. 2, and jointed at their rear ends to crank arms 21ⁱ on vertical rock shafts 21^s journaled in suitable bearings provided by a forwardly projecting portion 70 of the plate 21 and the horizontal portion of an angle bracket 21ⁱ similar to the brackets 21ⁱ and serving a similar function in guiding the uppermost stop rods 21^b. Spiral springs 21^u connecting the crank arms 75 21ⁱ with fixed studs on the plate 21 serve to draw the rods 21^a rearwardly and thereby hold the initial stop blades normally projected rearwardly from the plate 21 in the paths of the abutment pieces 60^a. Each vertical rock shaft 21^s has a series of nine lateral lugs 21^v projecting oppositely to the crank arms 21ⁱ and each of the stop rods 21^b is formed with a downwardly and rearwardly projecting finger 21^w in line with 85 one of said lugs and extending immediately in front of the same, as clearly illustrated in Figs. 1, 2 and 3. When an amount key is depressed and its stop rod thrust rearwardly the finger 21^w operates upon a lug 90 21^v and turns the shaft 21^s against the stress of the spring 21^u thus forcing the thrust rod 21^a forward and withdrawing the initial stop blade 21^c from the path of the abutment piece 60^a.

95 The amount keys are temporarily held in depressed position by the engagement of rounded lugs 21^x formed upon the sides of their stems, with wide pawls or shutters 21^y pivotally mounted under the keyboard plate 21^m in angle brackets 21ⁱ and 21ⁱ^a and drawn into engagement with the key stems by springs 21^z as shown in Fig. 4. There is one of these wide pawls or shutters for each row of keys and the depression of any key 100 in the row displaces the shutter by the engagement of the rounded lug 21^x with the same, and then the shutter springs in over the lug to hold the key depressed. Depression of another key in the row will of course 105 result in releasing the first depressed key. The shutters at their upper ends have inclined projecting portions 20 adapted to be operated upon with a camming effect by 110 studs 20^a on a rock shaft 20^b. The oscillation of this rock shaft by hand serves to release erroneously depressed keys and said shaft may also serve to effect an automatic 115 release of keys in the course of an operation 120 of the machine.

125 It will be seen that the broad substantial stop blades are well adapted for co-operation with the abutment pieces when the latter are moving in either direction. When a rack carrier is advancing, i. e. swinging upwardly, the upper right angle edge of its abutment piece will come squarely into contact with the under surface of the projected stop blade insuring a definite, positive and uniform positioning of the rack carrier. If 130

an early release of keys is to take place, permitting projection of a lower stop blade at a time when the abutment piece is upwardly beyond it, then in the ensuing downward 5 swing of the rack-carrier, the beveled front edge of the abutment piece will wipe down over the blade, the spring 60° yielding until the upper edge of the abutment piece has passed by, when the latter instantly snaps 10 forward to come squarely into contact with the blade when the rack carrier again advances.

It will further be seen that the arrangement of keys and stop rods provides for 15 operative action between the keyboard section or department of the machine and registering or adding mechanism located to the rear and not extending under the keyboard, which may thus be as low as desired, 20 the arrangement furthermore permitting location of the adding wheels just upwardly beyond the keyboard where they can be conveniently read.

The direct interconnection between amount 25 stops and zero stops insures the latter's always standing ready to intercept the rack carriers unless amount keys have been depressed, and vice versa, insures the complete withdrawal of zero stops when amount 30 keys are depressed.

Finally it is to be noted that the construction throughout is compact and easy to assemble and handle as a distinct section or department of the machine; that there is 35 practically no chance for derangement of parts; and that the character of the several parts and their relative arrangement make for great stability and durability.

What is claimed is:

- 40 1. In a machine of the character described, the combination of a reciprocating actuator having a pass-by abutment piece, and a series of normally retracted stop blades adapted to be projected into the path of said 45 abutment piece to limit the advance movement of the actuator, the abutment piece adapted to pass by a projected stop blade in the return movement of the actuator and then reassume position for abutting the 50 same in advance movement of the actuator.
2. In a machine of the character described, the combination of a reciprocating actuator having a pass-by abutment piece, a series of normally retracted stop blades adapted to 55 be projected into the path of said abutment piece to limit the advance movement of the actuator, the abutment piece adapted to pass by a projected stop blade in the return movement of the actuator and then reassume position for abutting the same in advance movement of the actuator, a normally projected zero stop blade, and means for 60 retracting the latter by projection of one of the first mentioned stop blades.
- 65 3. In a machine of the character described,

the combination of a reciprocating actuator having a pass-by abutment piece, and a series of normally retracted slide rods having stop blades adapted to be projected into the path of said abutment piece to limit the 70 advance movement of the actuator, the abutment piece adapted to pass by a projected stop blade in the return movement of the actuator and then reassume position for abutting the same in advance movement of the actuator. 75

4. In a machine of the character described, the combination of a reciprocating actuator having a pass-by abutment piece, a series of 80 normally retracted slide rods having stop blades adapted to be projected into the path of said abutment piece to limit the advance movement of the actuator, the abutment piece adapted to pass by a projected stop blade in the return movement of the actuator 85 and then reassume position for abutting the same in advance movement of the actuator, a slide rod having a zero stop blade normally projected into the path of the abutment piece, and operative connections 90 between such rod and the first mentioned rod for causing retraction of the former by projection of the latter.

5. In a machine of the character described, the combination of a reciprocating actuator 95 having a pass-by abutment piece, a series of normally retracted slide rods having stop blades adapted to be projected into the path of said abutment piece to limit the advance movement of the actuator, the abutment 100 piece adapted to pass by a projected stop blade in the return movement of the actuator and then reassume position for abutting the same in advance movement of the actuator, and depressible keys engaged with the 105 slide rods for advancing and retracting the same.

6. In a machine of the character described, the combination of a reciprocating actuator having a pass-by abutment piece, a series of 110 normally retracted slide rods having stop blades adapted to be projected into the path of said abutment piece to limit the advance movement of the actuator, the abutment piece adapted to pass by a projected stop blade 115 in the return movement of the actuator and then reassume position for abutting the same in advance movement of the actuator, and the slide rods having obliquely slotted portions; and spring upheld depressible keys 120 having studs engaging the slots of the rods respectively.

7. In a machine of the character described, the combination of a reciprocating actuator having a pass-by abutment piece, 125 a series of normally retracted slide rods having stop blades adapted to be projected into the path of said abutment piece to limit the advance movement of the actuator, the abutment piece adapted to pass by a project- 130

ed stop blade in the return movement of the actuator and then reassume position for abutting the same in advance movement of the actuator, a slide rod having a zero stop blade normally projected into the path of the abutment piece, and operative connections between such rod and the first mentioned rod for causing retraction of the former by projection of the latter, said connections comprising a shaft cranked to the zero rod and adapted to be turned by any one of the other rods.

8. In a machine of the character described, the combination of a reciprocating actuator having a pass-by abutment piece, a series of normally retracted slide rods having stop blades adapted to be projected into the path of said abutment piece to limit the advance movement of the actuator, the abutment piece adapted to pass by a projected stop blade in the return movement of the actuator and then reassume position for abutting the same in advance movement of the actuator, a slide rod having a zero stop blade normally projected into the path of the abutment piece, and operative connections between such rod and the first mentioned rod for causing retraction of the former by projection of the latter, said connections comprising a shaft having lateral projections to be acted upon by the first mentioned slide rods and a thrust rod connected to the zero slide rod and cranked to said shaft.

9. In a machine of the character de-

scribed, the combination of a reciprocating actuator, a series of normally retracted stop rods, a normally projected zero stop rod, and operating connections between the latter and the other rods comprising a rock shaft having lateral projections to be acted upon by the first mentioned rods respectively, and a thrust rod cranked to the shaft and connected with the zero rod.

10. In a machine of the character described, the combination of rows of vertical deppressible keys, horizontal slide rods having oblique slots engaged by said keys, said rods extending rearwardly from said keys and terminating in substantially vertical series of stops.

11. In a machine of the character described, the combination of a reciprocating actuator, a series of normally retracted stop rods arranged horizontally one above another, a similar though normally projected zero stop rod, keys operatively connected with the first mentioned stop rods for projecting the same respectively, and a vertical rock shaft having a series of lateral projections one for each of said first mentioned stop rods and adapted to be acted upon by them respectively, said rock shaft being operatively connected with the aforesaid zero stop rod for retracting the latter upon depression of any one of said keys.
